DISPLAY STAND

Howard J. Marschak, Evanston, Ill.
(855-865 North Ave., Chicago, Ill.)

Continuation of design application Ser. No. 75,529, June
26, 1963. This application May 24, 1965, Ser. No.
85,423

Term of patent 14 years

(Cl. D80—9)

This application is a continuation of my co-pending application, Serial No. D. 75,529, filed June 26, 1963, now abandoned.

I claim:

The ornamental design for a display stand, as shown.
